ANIMAL HEAD FORM

James N. Naulty, East Orange, N. J.

Application March 26, 1936, Serial No. 70,964

4 Claims. (Cl. 35—20)

This invention relates to the head forms used to give shape to animal furs.

These head forms should be relatively light in weight, flexible, so that they may be bent in various ways in forcing them into the head skin, resilient so that they will resume their shape and hold the skin properly stretched and so that they will yield in the handling of the completed fur. Coupled with such resiliency, they should be sufficiently firm and strong so that they will not collapse or crush either at the time of preparing the skin or in the subsequent use of the article.

The objects of the present invention are to provide a head form having the above and other desirable characteristics and which will be relatively inexpensive, adapted to be readily inserted in the skin, self-adjusting to properly fit the skin and constructed to readily receive and to securely hold the clamp which is usually applied to the finished animal head.

The foregoing and other desirable objects are attained by the novel features of construction, combinations and relations of parts hereinafter described, illustrated in the accompanying drawing and broadly covered in the claims annexed.

The drawing illustrates a practical commercial embodiment of the invention, but it should be understood that the structure may be modified and changed in various ways all within the true intent and broad scope of the claims.

Fig. 1 is a top plan view of an embodiment of the invention.

Fig. 2 is a longitudinal sectional view on substantially the plane of line 2—2 of Fig. 1.

Fig. 3 is a bottom plan view of the article.

Fig. 4 is a broken sectional detail on substantially the plane of line 4—4 of Fig. 1.

Figs. 5 and 6 are transverse sectional views on substantially the planes of lines 5—5 and 6—6 of Fig. 2.

One of the important special features of the invention is the construction of the form with a transverse frontal wall 7, of appreciable thickness and strength and extending uninterruptedly substantially from top to bottom of the article as indicated particularly in Figs. 2 and 4.

Projecting forwardly from the transverse wall 7, is a snout portion made up of a hollow rib 8, with flattened lateral projections 9, at the base of the same and a thin bottom wall 10, connecting the side portions 9, for a part of their length but terminating forwardly of the lower edge of wall 7, to leave a transverse slot 11, opening from the bottom upwardly into the hollow snout.

This open bottom construction leaves the snout flexible enough for manipulation in inserting and fitting it in the head skin and the hollow rib backed up by the fairly heavy full height transverse wall gives the structure sufficient strength and stability to be forced fully into the nose portion of the skin.

From the upper edge portion of the frontal wall 7, a thinner, arched skull forming wall 12, extends to the rear. This being light and thin is reinforced at the interior by an integral rib or bead 13, extending across the top of the frontal wall and rearwardly about the top portion of arched wall 12.

The transverse frontal wall 7 stiffens the structure transversely and closes off the hollow snout portion. The opening 11 in the bottom of the snout portion provides an entrance for the upper jaw of the spring clamp which is ordinarily used with a skull form of this type and the lower edge of the frontal wall acts more or less as a stop to hold the inserted jaw in place.

The lower edge of the transverse wall 7 is indicated as bevelled or forwardly tapered at 14, toward the bottom opening 11, to facilitate the entrance of the "stick" or tool, which is used for forcing the form into the skin and to operate with a wedge effect for opposing the withdrawal of the clamp jaw when that is inserted in place.

Fig. 4 shows how the artificial eyes 15, may be secured by forcing the pins of the same through the frontal wall and bending them over on the inside as indicated at 16.

The device may be readily molded at low cost in a single integral piece of rubber composition material and constructed as disclosed, it is desirably light and flexible and yet at the same time is sufficiently strong and durable for the intended purposes.

The usual more or less straight length clamps, such as employed in the trade may be used with the form but, as indicated in Fig. 2, if desired, the upper jaw of the clamp may be angled or offset upwardly at 22, to pass up through the bottom slot 11 and form an abrupt shoulder standing in front of the lower edge of the wall 7. Similarly, the rearward handle portion of the upper jaw may be offset upwardly as at 23, to form a shoulder standing in back of this wall. This clamp then is locked in position by the transverse wall against movement in either direction. By extending continuously all the way to the lower edge of the article, the transverse wall 7 forms a barrier preventing any stuffing material that may be used in the hollow skull por-

tion from passing into the hollow snout or interfering with the insertion or operation of the clamp.

What is claimed is:

5 1. A form for the head skin of an animal fur, comprising a one piece integral hollow skull formation of a material having the characteristics of rubber and including an approximately vertical transverse frontal wall of substantially uniform thickness and extending continuously across the interior of the skull formation practically the full height of the article, a hollow snout portion projecting forwardly from said frontal wall and having a bottom wall with a transverse slot opening upwardly into the hollow snout, in front of said transverse substantially vertical frontal wall to receive the upper jaw of a holding clamp and a light flexible thin dome wall portion extending rearwardly in arched form from the upper part 10 of said frontal wall.

2. A form for the head skin of an animal fur, comprising a one piece integral hollow skull formation of a material having the characteristics of rubber and including an approximately vertical transverse frontal wall of substantially uniform thickness and extending continuously practically the full height of the article, a hollow snout portion projecting from said frontal wall and having a bottom wall separated from the 15 lower edge of the frontal wall by a space providing a bottom entrance up into the hollow snout portion, in front of the substantially vertical frontal wall for the upper jaw of a holding clamp, a light flexible thin dome wall portion 20 extending rearwardly in arched form from the 25 upper part of said frontal wall.

upper part of said frontal wall and a reinforcement about the top of said arched thin wall dome portion for yieldingly holding the same to shape.

3. A form for the head skin of an animal fur, comprising a one piece integral hollow skull formation of a material having the characteristics of rubber and including an approximately vertical transverse frontal wall of substantially uniform thickness and extending continuously practically the full height of the article, a hollow snout portion projecting from said frontal wall and having a bottom wall separated from the lower edge of the frontal wall by a space providing a bottom entrance up into the hollow snout portion, in front of the substantially vertical frontal wall 10 for the upper jaw of a holding clamp, a light flexible thin dome wall portion extending rearwardly in arched form from the upper part of said frontal wall, the lower edge of said frontal wall being bevelled forwardly toward said bottom 15 opening.

4. In combination, a form for the head skin of an animal fur, comprising an approximately vertical transverse frontal wall of substantially uniform thickness and extending continuously practically the full height of the article, a hollow snout portion projecting from said frontal wall and having a bottom wall separated from the lower edge of the frontal wall by a space forming a bottom entrance up into the hollow snout portion and a clamp having an upper jaw formed with an upwardly offset portion disposed in said bottom opening in front of said frontal wall.
